UNITED STATES PATENT OFFICE.

JOHN HENRY DIGGLE, OF LASALLE, ILLINOIS.

PROTECTING DEVICE FOR INDUCTION-MOTORS.

SPECIFICATION forming part of Letters Patent No. 703,902, dated July 1, 1902.

Application filed October 21, 1901. Serial No. 79,444. (No model.)

To all whom it may concern:

Be it known that I, JOHN HENRY DIGGLE, a citizen of the United States, residing at La-salle, in the county of LaSalle and State of Illinois, have invented certain new and useful Improvements in Protecting Devices for Induction-Motors; and I do hereby declare the following to be a full, clear, and exact description of the invention, such as will enable others skilled in the art to which it appertains to make and use the same.

This invention pertains to induction-motors; and it has for its object, primarily, to provide a simple and cheap yet most efficient and effective and durable protecting device for an induction-motor, particularly for three-phase induction-motors. Ordinarily these motors require a starting-current of from four to six times full-load current until they attain full speed. Usually as installed these motors are connected to the line by means of a switch and fuse-block. In order to start the motor, the fuse in the fuse-block has to be strong enough to carry from four to six times full-load current for a short time—say a few minutes, or until the motor has reached full speed—and it will therefore be readily seen that such a fuse affords practically no protection to the motor from heavy overloads.

My present invention, therefore, has for its object, among others, to provide means whereby the motor may be started either with a heavy fuse or its equivalent having a carrying capacity equal to that required for the starting-current, and when the motor has acquired full speed to cut this fuse out of the circuit, and the current thus allowed to travel through a smaller fuse sufficient to prevent or protect the motor from overloads or heavy rushes of current.

Other objects and advantages of the invention will hereinafter appear, and the novel features thereof will be specifically defined by the appended claims.

The invention in its preferred form is clearly illustrated in the accompanying drawings, which, with the numerals of reference marked thereon, form a part of this specification, and in which—

Figure 1 is a front elevation of a switch-

board, showing my improvements. Fig. 2 is a side elevation thereof.

Like numerals of reference indicate like parts in the different views.

Referring to the details of the drawings, 1 designates the switchboard, provided with an insulating-base 2. 3, 4, and 5 are the terminals secured to said base, and 6 designates the light fuses disposed between the poles of the switch, as is clearly shown in the drawings. 60 The fuses in this instance are shown as inclosed fuses, secured to the terminals by means of screws 7; but it is evident that any other suitable form of fastenings may be employed; also, the fuses can be almost any style, 65 either open or inclosed, as may be found most expedient.

8 designates the heavy fuses, which may be made of any material suited to the purpose, shown in this instance as being the switch-blades, pivotally mounted, as at 9, and provided with a suitable handle 10. When the switch is closed, these heavy fuses or switch-blades, which in some instances I make of copper, are designed to carry the bulk of the 75 current until the motor has acquired full speed, when the switch is opened and the light fuses will carry the current.

From the foregoing description when taken in connection with the annexed drawings the operation and advantages of my invention will be readily understood. It will effect a saving in the wear of the motor, it will not add materially to the cost, and its numerous advantages will be manifest to those familiar 85 with this class of devices.

The base or switchboard is shown as provided with suitable openings for the passage of the screws or other means that may be employed to secure the switch in any desired 90 place in any position required.

The size and shape of the switchboard may be varied as occasion may require. Neither is the present invention confined to the application thereof to a three-phase motor. 95

From the above it will be evident that I have devised a simple and cheap novel form of switchboard and protecting device for induction-motors, and while the structural embodiment of the invention as herein disclosed 100

is what I at the present time consider the preferable one it is evident that changes, variations, and modifications may be resorted to without departing from the spirit of the 5 invention or sacrificing any of its advantages, and I therefore do not wish to restrict myself to the details of construction hereinbefore described and as shown in the accompanying drawings, but reserve the right to make such 10 changes, variations, and modifications as come properly within the scope of the protection prayed.

What is claimed as new is—

1. A protecting device for induction-motors, comprising fuses connected with the terminals of the switchboard, and pivoted independent fuses and a handle carrying the 15

same to bring them in line with and over the first-mentioned fuses, substantially as and for the purpose specified.

20

2. A switchboard having an insulating-base, terminals, fuses connected to said terminals, and pivoted fuses to lie in the plane with and adapted for use in connection with said fuses or removable to allow the said fuses 25 to act independently after the motor has acquired the predetermined speed, as set forth.

In testimony whereof I affix my signature in presence of two witnesses.

JOHN HENRY DIGGLE.
